UNITED STATES PATENT OFFICE.

JONATHAN R. SPENCER, OF AVILLA, MISSOURI.

BROOM-HEAD.

SPECIFICATION forming part of Letters Patent No. 226,124, dated March 30, 1880.

Application filed May 27, 1879.

To all whom it may concern:

Be it known that I, JONATHAN R. SPENCER, of Avilla, in the county of Jasper and State of Missouri, have invented certain new and useful Improvements in Broom-Heads; and I do hereby declare that the following is a full, clear, and exact description of the invention, which will enable others skilled in the art to which it appertains to make and use the same, reference being had to the accompanying drawings, which form a part of this specification, and in which—

Figure 1 is a side elevation of my improved broom-head. Fig. 2 is an end or edge view. Fig. 3 is a bottom view. Fig. 4 is a longitudinal section, and Figs. 5^a and 5^b are sections of the tubular adjustable draw-bolts which form a part of my improvement.

Similar letters of reference indicate corresponding parts in all the figures.

This invention relates to that class of broom-heads in which the broom-corn is clamped between two plates or frames secured upon the end of the handle; and it consists in the combination of the handle, clamping-plates, and tubular draw-bolts, substantially as hereinafter more fully set forth.

In the drawings, A is the broom-handle, which is tapered off, as shown at a, at its lower end, which is inserted into the head. This is formed by two frames or skeleton plates, B B', united by the adjustable draw-bolts C C.

The upper part of each of the frames B B' has a semicircular collar, b b', impinging upon the lower round part of the handle A, and secured thereto by strong cord or wire c.

Each of the draw-bolts C consists, preferably, of two parts—viz., a tubular shank, d, having a head, e, at one end, and provided with an inner screw-thread, and a screw, f, which fits into the screw-threaded tube d, and is, in like manner, provided with a head, g.

The screw f, which works in the screw-threaded tube d, may be made in one or in two parts, as shown in Figs. 5^a and 5^b, respectively. If made in two parts, tube d is made without a head, in place of which each of the screw-sections f is provided with a head, g g, as shown clearly in Fig. 5^b.

These draw-bolts are arranged in the head in the manner shown in Figs. 1 and 4—that

is, one on each side of the handle in the upper part of the head, one in the middle of the lower part of the head, which passes through a perforation in the tapering part a of the handle, and one in each lower corner of the head. In filling the head plates B B' are loosened by unscrewing the screws f of bolts C, the heads of which, as well as the heads of the tubes d, are fitted in countersunk perforations in their respective frames or plates, so that the head will present a smooth and finished appearance. It is not necessary to withdraw the screws from their tubes, as without this the plates B B' will be a sufficient distance apart to permit of the insertion of the broom-corn, which is placed between the two plates on each side of the handle, a bunch of long straw or similar material having first been placed in the head, close up against and around the handle. After the head has been filled the plates B B' are tightened down by turning the screws f back into their tubes d, when a solid and compact head is formed.

I prefer to place two rows of stitching below the head, about two and three inches, respectively, below the lower rim of the head, which makes a very strong and durable broom of a neat and finished appearance.

I am aware that tubular draw-bolts have been used before in the construction of broom-heads, and I do not claim such construction broadly; but,

Having thus described my improvement, I claim and desire to secure by Letters Patent of the United States—

In a broom-head, the combination, substantially as set forth, of the handle A, having tapering perforated section a, detachable clamping-plates B B', provided with semicircular collars b b', and detachable tubular and adjustable draw-bolts C, arranged in plates B B' with reference to said plates and to the perforated tenon a of the handle A, as shown and described.

In testimony that I claim the foregoing as my own I have hereunto affixed my signature in presence of two witnesses.

JONATHAN R. SPENCER.
